UNITED STATES PATENT OFFICE.

HENRY L. DOERING, OF ERIE, PENNSYLVANIA, ASSIGNOR TO BALL ENGINE COMPANY, OF ERIE, PENNSYLVANIA, A CORPORATION OF PENNSYLVANIA.

POWER SHOVEL.

Application filed February 23, 1921. Serial No. 447,264.

To all whom it may concern:

Be it known that I, HENRY L. DOERING, a citizen of the United States, residing at Erie, in the county of Erie and State of Pennsylvania, have invented new and useful Improvements in Power Shovels, of which the following is a specification.

The shovel forming the subject of this invention is particularly designed for digging trenches and here it is desirable to have the shovel in advance of the trench so that it may be supported on the ground to be dug. The difficulty is to so handle the dipper as to cut in this relation and still have it so that it may be emptied with convenience and certainty. In the present invention this is accomplished.

The invention is illustrated in the accompanying drawings as follows:

Fig. 1 shows a side elevation of the shovel.

Fig. 2 a view with the dipper in an elevated position prior to emptying.

Fig. 3 a view of the position of the dipper after it is swung to position to empty.

1 marks the shovel frame, 2 the usual rotating platform, 3 a boom mounted on the front end of the platform, and 4 the supporting rod for the boom, this rod extending over the strut 5 to the platform.

The dipper stick 6 is of the usual construction. It has a rack 7 along one face operating on a gear 8. The dipper stick is handled by a crowding engine 9 mounted on the boom, the engine operating the crank shaft 10 and the crank shaft 10 being connected by a gear (not shown) with a gear 11. The gear 11 is on a shaft 12 which also carries the gear 8.

A hoisting cable 13 operates over a pulley 14 at the upper, or outer end of the boom and is carried over a drum 15, the drum being actuated from a gear 16 and the gear being driven from an engine 17 in the usual manner. A pull-in cable 18 is carried over a pulley 19 on the lower end of the boom to a drum 20. The drum 20 is driven from a gear 21 which is connected with the gear 16, or other convenient mechanism with the engine in the usual manner. These drums have the usual control actuated by the levers 15^a and 20^a so that the drums may be released or thrown into operation as desired and each drum is supplied with the usual

brake actuated by the brake pedal 18^a. These parts are well known and are ordinary parts of a steam shovel. A bracket 22 is fixed on the end of the dipper stick and a dipper 23 is pivotally mounted by means of a pin 24 on the bracket 22. A cover 25 extends from the bracket and is fixed relative to the bracket, being held in place by a brace 26 extending from the cover back to the bracket. The bracket has an extension 27 on the end of which is a stop 28 which limits the swinging of the dipper relative to the dipper stick so as to position the cutting edge 23^a of the dipper with relation to the dipper stick.

The pull-in cable 18 runs under a pulley 29 in the bracket 22 and over a pulley 30 and is secured to the rear end of the dipper.

It will be observed that the cutting edge of the dipper faces the platform. In operation after the dipper stick is lowered through the action of the cable 13 as it is played out the pull-in line 18 is drawn in, thus swinging the dipper toward the platform and carrying the cutting edge into the face of the trench. The vertical position of the dipper during this action may be conveniently controlled by the crowding engine. After the dipper has received its load

the haul-in line 18 is released and the pull up line 13 is operated and the crowding engine is held so that the dipper swings on the gear 8 as a pivot upwardly. As the dipper stick swings upwardly the dipper through gravity swings on the pivot 24 until the front face of the dipper engages the cover 25. At the extreme upward lift of the stick the dipper and parts are in the position shown in Fig. 2. The dipper is held in this position, the boom swung over to the side and the pull-in line is then put under strain and this pulls the rear end of the dipper up to the stop 28, thus inverting the dipper and swinging it away from the cover so that the material in the dipper is emptied. The dipper is then swung over the trench and the hoisting line released allowing the dipper to drop to the face of the work and the operation is repeated.

It is desirable when the dipper is opened in order to assist in the easy handling of the cables to catch the dipper in the open position after it is emptied and for this

purpose a catch 31 is arranged on the dipper in position to be engaged by a latch 32. The latch is pivoted on the pin 33 in the bracket 22 and has a weight 34 which tends to hold the latch in engagement with the catch. In this way the line 18 may be freely released as the dipper is lowered to its work. When it has reached the position to operate, the weight 34 passes over the center of the pivot 33 and thus moves the latch out of engagement with the catch. The pull-in line holds the dipper in position with the stop as it is advanced into the work.

What I claim as new is:—

15. 1. In a power shovel, the combination of a shovel platform; a dipper stick; devices for actuating the stick from the platform; a dipper pivoted on the stick and having its cutting edge facing the platform; and a line 20 connected with the dipper and directioned to act as a pull-in line to effect the cutting movement of the dipper, said line swinging the dipper to empty the same.

2. In a power shovel, the combination of a shovel platform; a dipper stick; devices for actuating the dipper stick from the platform; a dipper pivoted on the stick and having its cutting edge facing the platform; and a stop limiting the relative movement 30 between the stick and dipper to position the cutting edge of the dipper relatively to the work.

3. In a power shovel, the combination of a shovel platform; a dipper stick; devices 35 for actuating the dipper stick from the platform; a dipper pivoted on the stick and having its cutting edge facing the platform; and a stop limiting the swinging movement of the dipper to hold the dipper 40 relatively to the stick as the dipper is advanced into the work.

4. In a power shovel, the combination of a shovel platform; a dipper stick; devices actuating the stick from the platform; a 45 dipper pivoted on the stick and having its cutting edge facing the platform; a stop limiting the movement of the dipper relative to the dipper stick; and a line actuated from the platform and connected to the dipper for swinging the dipper against the stop.

5. In a power shovel, the combination of a shovel platform; a dipper stick; devices actuating the stick from the platform; a 55 dipper pivoted on the stick and having its cutting edge facing the platform; a stop limiting the movement of the dipper relative to the dipper stick; and a line actuated from the platform and connected to the dipper for swinging the dipper against the stop, said line being positioned to act as a pull-in line.

6. In a power shovel, the combination of a shovel platform; a dipper stick; devices 65 for actuating the stick from the platform; a

dipper pivoted on the stick and having its cutting edge facing the platform; a guiding means on the stick; and a cable extending over the guiding means connected with the dipper for swinging the dipper relatively to the stick.

7. In a power shovel, the combination of a shovel platform; a dipper stick; devices for actuating the stick from the platform; a dipper pivoted on the stick and having its cutting edge facing the platform; a guiding means on the stick; a cable extending over the guiding means connected with the dipper for swinging the dipper relatively to the stick; and a stop for positioning the dipper as it is actuated by the cable.

8. In a power shovel, the combination of a shovel platform; a dipper stick; devices for actuating the stick from the platform; a bracket arranged on the stick; a dipper pivotally mounted on the bracket; a stop on the bracket limiting the swinging movement of the dipper; pulleys mounted on the bracket; and a cable carried under one pulley and over another on the bracket and connected 90 with the dipper in position to move the dipper against the stop.

9. In a power shovel, the combination of a shovel platform; a dipper stick; devices for actuating the stick from the platform; a dipper pivoted on the stick and having its cutting edge facing the platform; means for swinging the dipper on the stick to move it to cutting position and to empty the same; and a catch for locking the dipper with the 100 stick in one position and automatically releasing the stick in another position.

10. In a power shovel, the combination of a shovel platform; a dipper stick; devices for actuating the stick from the platform; a dipper pivoted on the stick and having its cutting edge facing the platform; means for swinging the dipper on the stick to move it to cutting position and to empty the same; and a catch for engaging the dipper and 110 locking it with the stick as the dipper is swung to emptying position and automatically releasing the dipper as it is swung to cutting position.

11. In a power shovel, the combination of a shovel platform; a dipper stick; devices for actuating the stick from the platform; a dipper pivoted on the stick and having its cutting edge facing the platform; means for swinging the dipper to cutting position and 120 to emptying position; and a cover against which the dipper swings as the dipper stick is elevated.

12. In a power shovel, the combination of a shovel platform; a dipper stick; devices for actuating the stick from the platform; a dipper pivoted on the stick and having its cutting edge facing the platform; means for swinging the dipper to cutting position and 125 to emptying position; and a cover against 130

- which the dipper swings by gravity as the dipper stick is elevated.
13. In a power shovel, the combination of a platform; a dipper stick; devices for actuating the stick from the platform; a dipper pivotally mounted on the stick; a line connected with the dipper and adapted to swing the same to emptying position, said line acting as a pull-in line; and a cover fixed on the stick in position to close over the dipper as it swings with the lifting of the stick.
- In testimony whereof I have hereunto set my hand.

HENRY L. DOERING.
